UNITED STATES PATENT OFFICE

142,847

DESIGN FOR A SHOE

Joseph P. Famolare, Chestnut Hill, Mass.

Application July 31, 1945, Serial No. 121,102

Term of patent 14 years

(Cl. D7—7)

To all whom it may concern:

Be it known that I, Joseph P. Famolare, a citizen of the United States, residing at Chestnut Hill, in the county of Middlesex and Commonwealth of Massachusetts, have invented a new, original, and ornamental Design for a Shoe, of which the following is a specification, reference being had to the accompanying drawing, forming a part thereof, in which:

Fig. 1 is a plan view of a shoe showing my new design; and

Fig. 2 is a side elevational view, slightly in perspective.

The areas of ornamentation shown on parts of the shoe extend over the entire outside of the shoe upper.

I claim:

The ornamental design for a shoe, substantially as shown and described.

JOSEPH P. FAMOLARE.
